BUILDING PANEL

Alden C. Wells, Kansas City, Mo.

Application October 7, 1946, Serial No. 701,639

2 Claims. (Cl. 20—5)

1 This invention relates to buildings of the character composed of a number of prefabricated units and pertains particularly to said units, each of which is composed of a number of shingles mounted upon a sheathing strip with a sheet of insulating material or vapor barrier.

One of the important objects of this invention is to provide a building panel capable of use as a portion of a building roof or side wall and having as a part thereof a sheathing strip upon which is mounted at least one course of shingles cooperatively assembled to allow the panel to operably associate itself with proximal panels during the erection of the building.

Further objects of the invention, including the form, disposition and advantages arising from the use of the aforementioned sheet, will appear during the course of the following specification referring to the accompanying drawings, wherein:

Fig. 1 is a fragmentary elevational view of a building wall composed of panels made in accordance with the present invention.

Fig. 2 is a sectional view taken on line II—II of Fig. 1.

Fig. 3 is a fragmentary face view of one of the panels having two courses of shingles but without the sheet of insulating material or vapor barrier.

Fig. 4 is an edge elevational view of a fragment of a building roof composed of a number of units; and

Fig. 5 is a fragmentary sectional view taken on line V—V of Fig. 3.

The building panel chosen for illustration comprises a sheathing strip 10 of a length agreeable to the distance between such building elements as the supporting rafters or studding designated by the numeral 12. The length of sheathing strip 10 should be such as to cause the ends thereof to position themselves at the approximate centers of the rafters or studding 12 as shown in Fig. 3. The sheathing 10 is chamfered along one longitudinal edge thereof to present a shoulder 14 and a downwardly and outwardly inclined face 16. One end of sheathing 10 is beveled as at 18 for the purpose more fully hereinafter described.

Shingles 20 arranged in two courses are secured to sheathing 10 by nails or analogous means 22. The course of shingles immediately on top of sheathing 10 is spaced inwardly from the beveled end of sheathing 10 but projects beyond the opposite end of the sheathing 10 as seen in Fig. 3. The uppermost course of shingle 20 overlies the shingles of the under-course and the ends of this upper course of shingles are disposed as clearly shown in Fig. 3. One end of the

2 upper course of shingles 20 projects beyond the end of sheathing 10 that is beveled as at 18, while the other end of the course of shingles 20 is located inwardly from both the end of sheathing 10 and the proximal end of the under-course of shingles 20.

When the building panel is constructed at the factory, only the courses of shingles 20 and the sheathing strip 10 are secured together for transportation. As application occurs, the sheathing 10 is nailed directly to rafters or studding 12 and another panel is brought into use by butting the sheathing 10 thereof against the end of the first-placed sheathing. When the subsequently placed

15 panel is moved against the end of a positioned panel, having bevel 18 formed on its sheathing 10, the lowermost course of shingles will have its outwardly projecting portion in alignment with the similar course of the panel first placed. It

20 is to facilitate the movement of the end shingle of the under-course thereof onto the top of sheathing 10 that bevel 18 is provided. If the outwardly projected end shingle of one of the undercourses thereof should happen to curl

25 slightly, bevel 18 will guide that shingle into the position shown in Fig. 5 where it will underlie the upper course of the first-placed panel. When such is accomplished, nails 24 are brought into play and driven into either the rafter or studding

30 12 as the case may be.

When another panel is to be moved beside a previously mounted panel, the ends of the upper course of the later applied panel are moved beneath the portions of shingles 20 constituting the lower course of the previously mounted panel.

35 As these upper-course shingles 20 are moved to position, their ends will enter the groove 26 formed by shoulder 14, inclined face 16 and the overlying shingles 20. This groove 26, by virtue of the inclination of surface 16, has an enlarged mouth and a groove of flaring characteristic functions to insure full and positive overlapping of the shingles comprising the two courses of adjacent panels.

40 The several panels needed to form a complete roof or side wall are interlocked along longitudinal edges and ends to affect an appreciable saving of time and labor at the point of building erection. No jamming will occur during the application of panel to the studding or rafters and matching joints are insured over the entire roof or wall area. Construction of the unit at the factory may be accomplished with equipment such as box nailing machines. When an eave

45 line is to be formed, the lower course of shingles

may be cut back flush with the second course. Four or eight foot panels are desirable and, when so constructed, may be crated through the use of boarding material. This crating material in turn may be employed on the job for the sheathing of valleys, corners or other special places.

Insulating material or a vapor barrier in the form of sheet 30 is a part of the units shown in Figs. 1 and 2. The sheathing 10 has its chamfered edge within the loop provided in sheet 30 when the marginal edge thereof is disposed between the upper face of sheathing 10 and the course of shingles next thereto. This sheet 30 extends across the face of sheathing 10 that lies against studding 12 and thence around the free ends of the other course of shingles 20 and across the faces thereof as shown in Fig. 2.

When the units are in place, that portion of the sheet 30 overlying the faces of shingles 20 of the outer-course thereof, is covered by the shingles of the lower-course of the unit next adjoining. A snug fit between the sheets of adjoining units in groove 26 is assurance that a weatherproof, continuous covering of insulating material and vapor barrier is present when the units made as shown in Figs. 1 and 2 are employed.

Having thus described the invention, what is claimed as new and desired to be secured by Letters Patent is:

1. A building panel comprising an elongated sheathing strip; and a pair of overlapping courses of shingles secured to one face of the strip and extending along the length thereof, the upper course of shingles projecting transversely beyond one longitudinal edge of the strip, the lower course of shingles projecting transversely beyond the opposite longitudinal edge of the strip, said courses of shingles being relatively offset, with said upper course extending beyond one end of

30

the strip and said lower course extending beyond the opposite end of the strip, that edge of said one end of the strip next adjacent said one face of the strip being beveled throughout the length thereof, whereby to facilitate insertion of said one end of the strip below the upper course of shingles of another building panel of like character with the proximal ends of the strips in abutting relationship.

10 2. In building structure of the kind set forth, a plurality of building units each comprising an elongated sheathing strip and a pair of overlapping courses of shingles mounted on one face of the strips and extending transversely thereof and laterally beyond each longitudinal edge, said units being adapted for mounting on a support with the courses of shingles of each unit interleaved with the proximal course of shingles of adjacent units; and a sheet of insulating material extending the entire length of each unit respectively, each sheet of insulating material extending from a point of securement on said one face of its sheathing strip, into looped relationship to one longitudinal edge of its sheathing strip, thence across the opposite face of its sheathing strip and terminating in secured relationship to one of the next adjacent units.

ALDEN C. WELLS.
